UNITED STATES PATENT OFFICE.

GEORGE H. LYTTLE, OF CLEVELAND, OHIO.

DESIGN FOR A BADGE.

SPECIFICATION forming part of Design No. 24,533, dated August 13, 1895.

Application filed May 31, 1895. Serial No. 551,331. Term of patent 3½ years

To all whom it may concern:

Be it known that I, GEORGE H. LYTTLE, a citizen of the United States, residing at Cleveland, in the county of Cuyahoga and State of Ohio, have invented and produced a new and original Design for Badges, of which the following is a specification, reference being had to the accompanying drawings, showing a part thereof.

Figure 1 is a front view of a button-badge, showing my design; and Fig. 2, an edge view of the same, these two views being deemed necessary to fully illustrate my design.

The leading feature of my design consists in a badge herein shown comprising a trefoil figure encircled by a C-shaped scroll, as clearly represented in the drawings.

The center of my design consists of the

three lobes 1 and the stem 2, forming what is commonly called a "trefoil," and what is known as a "club" in a deck of playing-cards. The trefoil, formed by the lobes 1 and the stem 2, is nearly encircled by the scroll 3, a segment of said band being removed adjacent to the right-hand lobe 1 to make the C shape of the scroll.

What I claim is—

The design for a badge as herein shown and described.

In testimony whereof I affix my signature in presence of two witnesses.

GEO. H. LYTTLE.

Witnesses:

F. A. CUTTER,
W. A. E. BERGHOFF.
